UNITED STATES PATENT OFFICE

172,864

HANDLE FOR STAPLING AIR GUN

Lee R. Campbell, Royal Oak, Mich.

Application January 13, 1954, Serial No. 28,500

Term of patent 14 years

(Cl. D74—1)

To all whom it may concern:

Be it known that I, Lee R. Campbell, a citizen of the United States and a resident of Royal Oak, county of Oakland, and State of Michigan, have invented a new, original, and ornamental Design for a Handle for Stapling Air Gun, of which the following is a specification, reference being had to the accompanying drawings, forming a part hereof, and wherein

Fig. 1 is a side elevation,
Fig. 2 is a front elevation,
Fig. 3 is a rear elevation,

Fig. 4 is a top plan view, and
Fig. 5 is a bottom plan view of a handle for
stapling air gun embodying my new design.

I claim:

The ornamental design for a handle for stapling
air gun, as shown.
